UNITED STATES PATENT OFFICE

146,579

DESIGN FOR A TABLECLOTH OR SIMILAR ARTICLE

Robert Laessig, New York, N. Y.

Application November 13, 1946, Serial No. 134,735

Term of patent 3½ years

(Cl. D92—26)

To all whom it may concern:

Be it known that I, Robert Laessig, a citizen of the United States of America, residing in New York city, county of New York, and State of New York, have invented a new, original, and ornamental Design for a Tablecloth or Similar Article, of which the following is a specification, reference being had to the accompanying drawing, forming part thereof.

The drawing shows a quarter portion of a tablecloth or similar article showing my new design, the other three quarters being identical therewith arranged in proper relation to complete the tablecloth.

I claim:

The ornamental design for a tablecloth or similar article, substantially as shown and described.

ROBERT LAESSIG.
